UNITED STATES PATENT OFFICE.

HARRY SWINGLEHURST, OF BOSTON, MASSACHUSETTS, ASSIGNEE TO SCOTT & WILLIAMS, INC., OF PHILADELPHIA, PENNSYLVANIA, A CORPORATION OF NEW JERSEY.

NEEDLE-CYLINDER FOR CIRCULAR-KNITTING MACHINES.

1,089,021.

Specification of Letters Patent.

Patented Mar. 3, 1914.

Application filed October 5, 1911. Serial No. 653,004.

To all whom it may concern:

Be it known that I, HARRY SWINGLEHURST, a citizen of the United States, and a resident of Boston, in the county of 5 Suffolk and State of Massachusetts, have invented an Improvement in Needle-Cylinders for Circular-Knitting Machines, of which the following description, in connection with the accompanying drawings, is a 10 specification, like characters on the drawings representing like parts.

This invention relates to needle cylinders for circular knitting machines.

In order that the principle of the invention may be readily understood, I have disclosed a single embodiment thereof in the accompanying drawing, wherein—

Figure 1 is a plan view of a needle cylinder embodying my invention; Fig. 2 is a 20 vertical, central section thereof; and Fig. 3 is a side elevation of a portion of the said cylinder.

The needle cylinder embodying my invention may be either of the rotary or stationary type; that is to say, it may be employed in machines where either the needle cylinder or the cam cylinder is rotated in the production of the work.

Needle cylinders have heretofore been built 30 up of three superposed rings, the middle ring being of greatest length and having applied to its outer face the needle spacing bars or walls which are held in position by the upper and lower rings. Such construction is objectionable in that the upper ring, 35 serving to hold in place the upper ends of the said spacing bars, is liable to become offset a little from its true position, thus twisting or displacing the said spacing bars. To 40 overcome this objection is one of the important purposes of my invention.

Referring more particularly to the drawings, the needle cylinder therein shown is represented as composed of a main or body 45 ring 1 and a lower or clamping ring 2 of suitable dimensions. I have herein shown a sinker cylinder 3 fitted into the upper end of the ring 1, but it is evident that my invention is applicable to needle cylinders not 50 employing sinkers or wherein the sinkers are otherwise mounted.

The main or body ring 1 is formed on its outer face with a series of grooves 4 corresponding in number to the number of

needles to be employed. Between the walls 55 of the grooves are inserted a corresponding series of bars 5 forming the walls of the needle grooves. These bars are of suitable thickness and of a width sufficient to cause them to project beyond the outer face of 60 the cylinder to permit the play of the needles therein during the knitting operation.

Preferably near its upper end the outer face of the ring 1 is provided with an annular shoulder 6 and at a suitable distance thereabove with a locking shoulder or abutment 7, preferably downwardly and outwardly inclined as shown. Between the shoulders 6, 7, is thus provided an annular recess to receive the heads 8 of the bars 5. Radially outside of the shoulder 7, there may be provided vertical slots or grooves 9, each wall whereof is herein shown as tapering at its lower end 10, the taper of 75 which may correspond to the taper of the wall 6, thus permitting the cutting or forming of these portions of the ring by a single rotary or other tool at one operation. Obviously the character of the recess between 80 the shoulders 6 and 7 may be changed to suit the shape of the heads 8 of the spacing bars 5. I preferably provide an annular groove 10' for the needle retaining band.

The ring 2 is provided with a shoulder or 85 abutment 11 here shown as tapering or inclined and corresponding to the inclination of the shoulder 12 upon the lower end of each spacing bar 5. The ring 2 may be secured in any suitable manner to the ring, as, 90 for example, by screws 13 tapped thereinto. If desired, the ring 2 may be provided with a flange 14 at its inner face to take into a corresponding annular recess 15 in the inner face of the ring 1. The shoulders or abutments 7 and 12 are inclined toward each other and receive between them the corresponding inclined portions of the needle bars or walls 5.

In assembling the parts, the bars 5 are 100 positioned in the grooves 4 with their upper and preferably inclined ends taking against the annular shoulder 7, the heads 8 being positioned between the shoulders 6 and 7. If desired, each bar 5 may be curved or inclined at its inner face, as represented at 105 16, to form a shoulder to cooperate with the adjacent shoulder 6, and may also be pro-

vided with a groove 17 to receive a second needle-retaining band. The clamping ring 2 is then placed in position, so that its shoulder 11 bears against the shoulders 12 of the bars 5. By tightening the screws 13, the heads 8 of the bars or walls 5 are forced tightly against the flange 7 of the ring 1. Inasmuch as said flange is integral with the ring 1, it is impossible to displace or deform the bars 5 in assembling the parts.

The bars 5 are locked in place by a minimum upward movement of the ring 2, owing to the provision of the fulcruming shoulders 6 in the bottom of the grooves in the needle cylinder, which shoulders coöperate with shoulders 16 on the bars 5, thereby tending to turn each bar 5 about the shoulder 7 as a center, throwing the bar outwardly with respect to its groove at the lower end thereof. I am thus enabled to lock the bars 5 tightly in place even if they vary slightly in length, and to avoid placing excessive strain upon them in the direction of their length, which would cause them to buckle and cramp the needle grooves formed between them. By employing merely the two rings 1 and 2, I am enabled to employ longer needle bars, and hence to guide the needles more effectively.

It is important that I provide means, such as the ring 2, for forcing the bars 5 upward instead of merely binding the lower ends of the bars by inward pressure, as has been proposed, and also it is important that the construction be such that the ring 2 may force the bars 5 against an absolutely fixed part,—that is, against an integral part of the ring 1 instead of against a third ring mounted upon the ring 2, and which might readily be displaced radially with respect to the ring 1.

The sinker cylinder 3 may be of any suitable character and construction, such, for example, as that shown in the patent to George D. Mayo, No. 726,178, April 21, 1903. Said sinker cylinder is provided on its outer face with a series of sinker receiving slots or grooves 18 corresponding in number to the needle receiving grooves of the ring 1. Viewing Fig. 3, it will be evident that the sinker grooves of the sinker cylinder are slightly offset circumferentially with respect to the grooves of the needle cylinder; that is, with the spaces between the bars 5 thereof,

thus permitting the proper play of the 55 sinkers between the needles.

It will be evident from the foregoing description that the needle cylinder embodying my invention can be cheaply and expeditiously formed, and at the same time all the 60 parts are held rigidly in intended position.

Having thus described one illustrative embodiment of my invention, I desire it to be understood that although specific terms are employed, they are used in a generic and descriptive sense and not for purposes of limitation, the scope of the invention being set forth in the following claims.

Claims.

1. A needle cylinder for knitting machines consisting of two superimposed rings, the uppermost thereof being provided with vertical peripheral grooves, bars 5 positioned within said grooves, the upper portion of said uppermost ring having a pivotal 75 shoulder 7 and fulcruming shoulders 6, and the lower ring having a shoulder for imparting upward thrust to said bars 5.

2. A needle cylinder for knitting machines consisting of two superimposed rings, 80 the uppermost thereof being provided with vertical, peripheral grooves, the upper portion of said ring having integral therewith two annularly opposed spacing shoulders, needle bars or walls inserted in said grooves 85 with their heads positioned between said shoulders, and the lowermost ring having an annular formation to engage the lower ends of said bars.

3. A needle cylinder for knitting machines consisting of a plurality of superimposed rings, one of them having vertical peripheral grooves, bars positioned within said grooves, one of said rings having an abutment for the upper ends of the bars and 95 another ring having an opposed abutment for the lower end of the bar, there being fulcruming shoulders in the bottoms of said grooves adjacent one of said abutments to co-act with the latter.

In testimony whereof, I have signed my name to this specification, in the presence of 100 two subscribing witnesses.

HARRY SWINGLEHURST.
